H. I. WRIGLEY.

DRAFT PLATE FOR RAILWAY CARS.
APPLICATION FILED AUG. 16, 1913.

1,101,228.

Patented June 23, 1914.

UNITED STATES PATENT OFFICE.

HENRY I. WRIGLEY, OF CHICAGO, ILLINOIS, ASSIGNOR TO UNIVERSAL DRAFT GEAR ATTACHMENT CO., OF CHICAGO, ILLINOIS, A CORPORATION OF ILLINOIS.

DRAFT-PLATE FOR RAILWAY-CARS.

1,101,228.

Specification of Letters Patent. Patented June 23, 1914.

Application filed August 16, 1913. Serial No. 785,055.

To all whom it may concern:

Be it known that I, HENRY I. WRIGLEY, a citizen of the United States, and resident of Chicago, county of Cook, and State of Illinois, have invented certain new and useful Improvements in Draft-Plates for Railway-Cars, of which the following is a specification, and which are illustrated in the accompanying drawings, forming a part thereof.

10 The invention relates to plates for attachment to the draft sills of a railway car for the purpose of receiving the pulling and buffing strains transmitted through the coupler.

15 The improved plate is especially adapted for use in connection with cars of wood construction; and its object is to provide for adequate strength and effective thickness without massing the metal, and also to provide an improved form of intermediate stop or limiting lugs whereby uniform thickness of metal is obtained, the formation of T-sections mainly avoided, and the necessary strength secured.

20 A further advantage accruing from the improved form of stop lug is the avoidance of much of the core work heretofore found necessary in the manufacture of castings of this character.

25 The invention is illustrated in the accompanying drawings, in which—

Figure 1 is a detail plan view, partly in section, of the center and end sills of a car and the draft rigging mounted thereon; Fig. 2 is a face view of one of the draft plates; Fig. 3 is a detail in perspective of a portion of the draft plate showing one of the stop lugs with some parts broken away; and Fig. 4 is a detail in perspective of the 40 same portion of the plate viewed from the rear.

It is the usual practice, in the manufacture of cars of wood, to secure the draft plates to the inner faces of a pair of draft timbers mounted immediately below the center sills. For added strength the draft plates are usually provided with upstanding horns which bear against the inner faces of and are bolted to the center sills, the forward horn abutting against the rearward face of the end sill of the car. In the drawings a draft plate of this form is shown.

One of the center sills of a car is represented at 10, and at 11 there is shown one of the draft sills, the center sill with which

it is associated being omitted. The end sill is represented at 12. The coupler shank is shown at 13 and the yoke at 14. A pair of tandem springs is shown at 15, 16, the forward spring 15 being located between a pair 60 of followers 17, 18, and the rearward spring 16 between a pair of followers 19, 20.

The body of the draft plate is represented at 21. It is of uniform thickness but is composed of a plurality of longitudinally disposed sections, as 22, 23, alternate sections being offset backwardly and forwardly, respectively, with reference to the median vertical plane of the plate, thereby increasing the effective thickness of the plate without 70 increasing its weight or requiring the massing of metal to produce ribs for giving the plate the required thickness.

The several offset portions of the plate are of substantial width and present flat 75 faces, those, as 22, which are backwardly offset give the required area of bearing surface upon the sills, and those, as 23, which are offset forwardly from the bearing surfaces for the edges of the follower plates 80 and are sufficiently wide to avoid excessive wear. The plate being cast as an integral piece, the described form avoids any massing of metal, there being a uniform actual thickness of metal throughout, while 85 giving a maximum thickness of the plate as measured from the inner or front face of the instanding sections 23 to the rearward face of the backwardly offset sections 22, which is required in car practice, the 90 follower plates being of standard size.

The intermediate stop or limiting lugs which determine the range of movement of the followers and thus prevent undue compression of the springs are cast integral 95 with the plate, and their form is best shown in Fig. 3. Each of these stops may be described as comprising a pair of oblong rectangular sections 24, 25, each formed of instanding walls of uniform thickness with 100 the body of the plate, the two sections being spaced apart and the tops of their adjacent walls being united by a web 26 of the same thickness, this web being apertured, as shown at 27, to permit the entry of a bolt 105 for securing the plate to the sill. In casting this form the only core required is that which provides for the space intermediate of the two sections 24, 25, and covered by the web 26. While the walls of the stop thus 110

formed are light, adequate strength is secured to resist the most excessive stresses which may be imposed upon them. The plate is also provided with transverse backwardly projecting ribs 28, adapted to be gained into the timbers. These ribs are also cast as hollow or chambered oblong rectangles, reinforced, however, midway of their ends, as shown at 29, by an apertured bridge through which the securing bolt is passed. The ribs 28 are located immediately back of the intermediate stops, so that the bolt-hole through the bridge 29 is in line with the bolt-receiving aperture 27.

So much of the invention as appertains to the intermediate stops is not, however, claimed in this application, as it is made the subject of an application which is a division of this one.

The necessary draft shoulders 30, 31, 32 and 33 are formed upon the plate, the intermediate shoulders 31, 32, being formed by looping the body of the plate inward, and the end shoulders 30 and 33 being reinforced

by looping the body of the plate inward, as shown at 34, 35. The central loop forming the shoulders 31, 32, is reinforced by a plurality of bridges, as 36, so that these two shoulders act as a unit in resisting pressure 39 by either of the followers 18, 19. Bolt-holes 37, 38 and 39 are formed in the lower supporting walls of the several draft shoulders for the attachment of tie straps uniting the two draft plates of the car and supporting 35 the draft rigging. The upstanding horns for engagement with the center and end sills are shown at 40 and 41.

I claim as my invention—

A draft plate having its body portion of 40 substantially uniform thickness and composed of a plurality of longitudinally extending integral sections having flat surfaces, adjacent longitudinally parallel sections being offset, respectively, inwardly 45 and outwardly.

HENRY I. WRIGLEY.
